UNITED STATES PATENT OFFICE.

JOHN M. SCHILLING, OF CHICAGO, ILLINOIS, ASSIGNOR TO FRED PARKER, OF CHICAGO, ILLINOIS.

SIGN.

Application filed December 13, 1919. Serial No. 344,683.

To all whom it may concern:

Be it known that I, JOHN M. SCHILLING, a citizen of the United States, residing at Chicago, in the county of Cook and State 5 of Illinois, have invented a new and useful Improvement in Signs, of which the following is a specification.

My invention relates to an improved sign of the kind used for artificial illumination 10 by projecting light preferably from electric lamps, therethrough.

My sign is characterized by a construction which simplifies the manner of assembling the different characters and letters 15 in the same frame to spell different words as desired and retaining said characters in assembled relation and by my invention I also provide an improved appearance of sign of the kind under consideration.

20 My invention will best be understood by reference to the accompanying drawings in which—

Fig. 1 shows my sign in assembled relation in front elevation,

25 Fig. 2 shows in a view similar to Fig. 1 the assembled sign with some of the character elements removed and with the frame work in partial cross section to show the construction of the same,

30 Fig. 3 is a sectional view of the parts shown in Fig. 1 taken along the line 3—3,

Fig. 4 is a sectional view of the parts shown in Fig. 1 taken along the line 4—4,

35 Fig. 5 is a perspective view of one of the character elements of the sign to an enlarged scale,

Fig. 6 is a sectional view of the element shown in Fig. 5 taken along the line 6—6,

40 Fig. 7 is a back view to a somewhat reduced scale of the element shown in Fig. 5,

Fig. 8 shows in a view similar to Fig. 7 to a somewhat larger scale a different construction of element,

45 Fig. 9 shows in front perspective view to an enlarged scale a character element in which the character is provided with an enlarged outer face,

Fig. 10 is a back view of one of the spacing elements employed,

50 Fig. 11 is a sectional view of the element shown in Fig. 10 taken along the line 11—11,

Fig. 12 shows in a view similar to Fig. 1, a special construction of letters, and

55 Fig. 13 shows in a similar view a single

letter plate having a two-part letter of regular outline and special ties between the parts avoided by my invention.

Similar numerals refer to similar parts throughout the several views. 60

As shown in Figs. 1, 2, 3, and 4, the sign consists of a frame 15 made preferably of metal and of rectangular shape and adapted for use to enclose the front of a light box containing electric lamps for illuminating the sign, said box and electric lamps forming no part of the present invention and therefore not being shown. 65

The frame 15 is provided with a rectangular opening around the edges of 70 which, as more clearly shown in Figs. 3 and 4, channels are secured extending into the said frame to receive the sign elements.

An upper channel 16, preferably of sheet metal, is contained in the upper part of the frame the channel extending upwardly in said frame and having its front edge portion bent at 17 over the front edge of the opening in the frame 15, the back edge of 75

said channel being bent outwardly at substantially right angles to the adjacent edge of the channel as indicated at 18, to reinforce the channel construction. A lower channel 19 similarly formed engages the lower edge of the opening through the frame 15 the only difference being that the channel 19 is considerably shallower than the channel 16 for a purpose to be described. 80

85 Fig. 4 shows the channel 19 extending through the frame 15 and the channel 16 being formed similarly to the channel 19 and similarly secured to the frame 15. There is thus provided a channel construction extending entirely around the frame secured to the front wall thereof by

90 folding the edge of the channel members over said frame and preferably by soldering or brazing the parts together to reinforce the frame and adapt it to withstand the usage it receives in practice. 95

100 The upper and lower channels 16 and 19 receive and support sign elements 21 which are of a height somewhat greater than the height of the opening between the edge portions of the channels 16 and 19 extending through the front opening of the frame 15. The depth of the channel 19 is such that when the sign elements rest therein the upper edges of the sign elements are contained 105 in the channel 16, and the depth of the chan-

nel 16 is such that when the sign elements are raised as indicated for the letter E in Fig. 2 the lower edges of the sign elements clear the upper edge of the upper part of the channel 19 thus permitting the sign elements to be removed from the frame and other sign elements inserted therein as desired. The sign elements may have openings 22 cut through them in any desired conformation to represent characters or letters; and to distribute the light from the source of illumination through the said openings, I prefer to employ back of said openings individual plates 23 of translucent material, which plates are of substantially the height of the sign elements so that they may be inserted and removed from the channels 16 and 19 in the manner above described for the sign elements. Spacing elements 24 without light openings through them may be employed as desired to space the letters or characters of the sign, said spacing members being of substantially the same height as the sign elements and the translucent backing plates, said spacing members being preferably constructed of metal as are the sign elements. When the sign elements and spacing members are assembled in the desired relation in the channels in the manner above referred to they may be held in said position against lateral movement by a suitable locking device, such for example, as a screw 25 extending through the front wall of the frame and engaging the edge of the outside element or spacing member mounted in the sign.

As indicated in Figs. 5 and 6 each of the sign elements is made preferably of sheet metal and has one of its edges folded or bent as indicated at 21^a and has its other edge formed into an off-set flange 21^b, said flange being off-set sufficiently so that it engages and fits the bent edge 21^a of the adjacent sign element or spacing member. In this manner when the sign elements and spacing members are assembled in the frame their edges interlock and prevent the ready removal of the sign elements from the frame and in addition the overlapping flanges 21^b prevent the passage of light through the joints between said sign elements and spacing members. It will further be observed that the bent edge of the sign element and the off-set flange form between them a recess for receiving a backing plate of translucent material 23 and insures that the said backing plate is held in proper relation relatively to the opening through the sign element. As shown in Fig. 5 the light opening 22 formed through the sign element 21 has extending from its edges outwardly a strip of sheet material 26 bent to the conformation of the opening 22 and secured to the edge thereof. This serves to direct light from the opening outwardly and gives a

more substantial appearance to the character or letter formed in the sign element. The strip 26 preferably extends through the opening 22 and, as shown in Fig. 7 it has formed on its inner edge an outwardly extending flange 26^a engaging the flat surface of the sign element 21 and preferably secured thereto by means of solder or brazing. The flange 26^a may be continuous as indicated in Fig. 7, except at the angles in the edges of the light opening 22, where it is notched, to permit bending said strip to conform with said angles. When the strip is to be used in connection with rounded openings it is desirable to change the nature of this flange as shown at 26^b in Fig. 8, the construction of the sign element being in other respects the same. As shown in Fig. 8 the flange 26^b is notched in such a manner as to form a succession of teeth so that the strip 26^c may be bent in the form of a curve as desired with letters and characters having rounded edges. Another important advantage of forming the strip 26^c with tooth flanges is that the strip may be manufactured in quantity before being used and then cut up and used for any desired characters or letters whether straight sided or round sided. The flanges 26^a and 26^b are important in that they form a strong connection between the strip forming a border for the character or letter and the sign element as a result of which the strip is not readily separated from the sign element. The strip referred to preferably extends through the light opening in the sign element and the flanges referred to as formed on said strip are preferably secured to the back face of the sign element and in this manner the said strip may be secured to the sign element by brazing or soldering not only on the back of the sign elements but also on the front between the front face of the sign element and the outstanding portion of the strip.

In the construction of sign element 21^d shown in Fig. 9 I have provided a modified construction of the strip 26^d extending outwardly from and surrounding the opening 22^d consisting in forming on the outer edge of said strip a flange 27 which preferably is substantially parallel with the plane of the sign element 21^d. In this manner I give the characters or letters a substantial and solid appearance without interfering in any manner with the light passing through the opening 22^d.

By the construction described, the characters and letters of my sign are clearly visible, not only from directly in front of the sign but also from either end thereof since the inner surface of the bent strips is illuminated at night by the light passing through the light openings and in the daytime the outer surface of said strips produce the same

- condition of side visibility, particularly when said strips are painted or otherwise colored in contrast with the color of the outer surface of the sign elements and spacing members. The use of the flange referred to on the outer edge of said bent strips, increases the daylight visibility, particularly when said flange is distinctively colored or finished.
- 10 As shown in Figs. 10 and 11 the spacing member 24 is formed preferably in the same manner as the sign elements above referred to, the only difference being that there is no light opening through said spacing member.
- 15 It will be understood that while I have shown my sign as embodied above in a sectional construction that where desired, the light openings may be formed in the same plate to represent the various desired characters and letters in case a fixed sign is desired and that a continuous sheet of translucent material may be used back of the light openings forming the letters and characters if preferred or that said sheet of material
- 20 may be transparent instead of translucent although I find that translucent material gives better light diffusion through the letter and character openings. I prefer however to form the backing plate in sections as it is more readily handled, more readily shipped and less liable to breakage. It will also be understood that I may use the improved features of my sign construction either singly or in combination as above described.
- 25 In Fig. 13, a letter plate 28 is shown having the letter "O" formed therein, of regular conformation and ties or bridges 29 connecting the body portion of the plate with the otherwise loose opaque center or "island" 30 of the letter. The letter shown is representative of all letters of this class for example A, B, D, P, Q and R and the numerals 6, 8, 9 and 0, which I designate herein as closed characters to distinguish from other letters and numerals which may be designated as open characters. With each of these letters and numerals, when of regular construction, similar ties must be used to support the otherwise loose centers unless the centers are individually secured to the corresponding translucent plates. Where the ties are used, an unpleasant appearance is produced, since the ties produce extra shadows forming no part of the letter and numeral outline. Where the ties are not used and the centers are secured to the translucent plates, it is difficult to form and locate the centers to preserve the proper relation between their edges and the edges of the openings through the opaque letter plates. By my improved construction shown in Fig. 12, I avoid all these difficulties, by a special conformation of letters in the letter plates 31, such that the centers 32 are connected by
- 30 narrow portions 33 of the plates with said plates, said narrow portions in effect forming ties but at the same time constituting a part of the outlines of the special form of letters employed. These special ties therefore produce no unpleasant effect and at the same time serve to positively locate and hold the centers of the letters so that additional fastening devices are not required for said centers. In other respects the sign elements 70 may be formed in substantially the manner described for the sign elements shown in Figs. 1 to 9 inclusive and when so formed, the outstanding edge strips reinforce said narrow connecting portions to give stable 75 support to said centers.
- 35 While I have shown my invention in the particular embodiment above described, it will be understood that I do not limit myself to this exact construction as I may employ equivalents known to the art at the time of the filing of this application without departing from the scope of the appended claims.
- 40 What I claim is:
1. A character for a sign, comprising a plate having a light opening therethrough in the form of a closed character having an outer outline and a center, and a narrow supporting portion extending from the body 90 portion of said plate to said center forming a part of the outline of the character.
- 45 2. A character for a sign, comprising a plate having a light opening therethrough in the form of a closed character having an outer outline and a center, and a narrow supporting portion extending from the body portion of said plate to said center forming a part of the outline of the character, and a strip of sheet material upstanding from 95 said plate around the outline of said character, and reinforcing said narrow supporting portion.
- 50 3. A frame for receiving sign elements comprising a first channel frame of sheet metal having a central sight opening and having its back away from said opening, and a second channel frame of similar conformation disposed in the channel of said first frame and having flanges extending 100 through the opening of said first frame and secured to the edges of said first frame.
- 55 4. In a sign, the combination of a frame having a channel extending around the inner edge of its sides and ends, sign elements 105 for insertion in said side channels, said elements being shorter than the distance between the bottoms of said side channels, and one of said side channels being deeper than 110 the other to permit swinging said elements into position in said frame and retaining them in said position, said elements having overlapping edges extending transversely of the frame preventing swinging any one of 115 said elements in overlapped relation from 120
- 60 125
- 65 130

said frame individually, and clamping means at one end of said frame for holding said elements filling the frame in overlapped edge relation to prevent removal of the elements from the frame.

5. As a means for forming outstanding faces of sign characters, a strip of sheet metal having one edge turned at substantially right angles to form a continuous outward standing supporting flange, said flange being closely notched throughout its length, whereby said strip may be readily conformed to the straight and curved sides and bent at the angles of characters of any shape 10 without further adaptation.

6. As a character element for use in an electric sign having a light box with a display opening for receiving unit character elements in various combinations with unit 20 backing plates of light transmitting material readily interchangeable with different character elements, the combination of a base plate of sheet metal having an unobstructed opening therethrough in the form of a desired character, a sheet metal flange projecting outwardly from the base plate around the entire boundary of said character opening, and a second sheet metal flange projecting from the outer edge of said first flange 25 in a plane substantially parallel with said

base plate and away from the character opening between the parts of said first flange, whereby an unobstructed light beam in the form of the desired character may pass through said base plate and outwardly 35 between the parts of said first flange to and beyond the outer edge thereof and the desired character may be given substantial appearance by external illumination.

7. As a character element for use in an electric sign having a light box with a display opening for receiving unit character elements in various combinations with unit 40 backing plates of light transmitting material readily interchangeable with different character elements, the combination of a base plate of sheet metal having an unobstructed opening therethrough in the form of a desired character, and a sheet metal flange projecting outwardly from the base 45 plate around the entire boundary of said character opening, whereby an unobstructed light beam in the form of the desired character may pass through said base plate and outwardly between the parts of said flange 50 to and beyond the outer edge thereof.

In witness whereof, I hereunto subscribe my name this 8th day of December, A. D. 1919.

JOHN M. SCHILLING.
